UNITED STATES PATENT OFFICE.

FRITZ SCHRÖTER, OF BERLIN, GERMANY, ASSIGNOR TO SAFETY CAR HEATING & LIGHTING COMPANY, A CORPORATION OF NEW JERSEY.

ELECTRIC GAS-FILLED LAMP WITH GLOW DISCHARGE.

Application filed January 3, 1920, Serial No. 349,349, and in Germany May 4, 1915.

(GRANTED UNDER THE PROVISIONS OF THE ACT OF MARCH 3, 1921, 41 STAT. L., 1313.)

This invention relates to gaseous conduction lamps, and more particularly to lamps of the above nature having a content of a gas or gases of relatively high conductivity 5 at relatively low pressure.

One of the objects of this invention is to provide a simple and practical gaseous conduction lamp characterized by a relatively high efficiency of conversion of electrical energy into light. Another object is to provide a gaseous conduction lamp in which an effective and efficient use is made of the various luminous regions in the glow discharge taking place within the lamp. Another object is to provide a lamp of the above character which will be automatically protective of itself against excessive current values passing therethrough. Other objects will be in part obvious or in part pointed out herein- 20 after.

The invention accordingly consists in the features of construction, combinations of elements and arrangement of parts as will be exemplified in the structure to be herein- 25 after described, and the scope of the application of which will be indicated in the following claims.

In the accompanying drawing there is shown in the single figure a vertical central 30 cross-sectional view of a possible embodiment of this invention.

As conducive to a clearer understanding of this invention, it may at this point be noted that this invention relates particularly 35 to lamps of the gaseous conduction type in which a luminous discharge is adapted to be maintained between suitable electrodes in the lamp and by reason of the gaseous content within the lamp. The gas employed 40 within the lamp and through which the luminous discharge is adapted to take place may consist of a gas or gases of the helium group or, for example, may also consist of pure nitrogen. More particularly, it might 45 be noted that this invention deals with lamps of the above character adapted to be operated upon ordinary commercial voltages, such for example as 220, 440 volts.

In the operation of a gaseous discharge 50 device of the usual type there is found to exist a certain potential drop between the negative electrode or cathode and certain points in what is known as the negative glow, of the discharge between the two electrodes.

This potential difference is known as the cathode fall of potential and will have what may be termed a normal value when the conditions under which the device is operated are such that the entire cathode surface is not utilized in the production of the luminous discharge between the electrodes and as long as the ions reaching and impinging upon the surface of the cathode are allowed to partake of their mean free and unobstructed path. This voltage drop or potential difference between the cathode and the negative glow will under the above conditions be substantially independent of the pressure of the gas within the device and is existent as long as the resultant glow is not distributed 70 over the entire surface of the cathode but is confined to only a portion thereof. Such will be the case if the current values are relatively small.

If, however, the intensity of the current is increased to such an extent that the entire surface of the cathode becomes operative or effective to take part in the glow discharge and so that the entire cathode surface is substantially entirely covered with the glow, the cathode fall of potential or, in other words, the potential difference between the cathode and negative glow is found to increase relatively rapidly with the increase in the intensity of the current. The same effect may be brought about if the surface of the cathode is so arranged with respect to the anode that the ions impinging upon or reaching the cathode are prevented from taking their normal mean free path. Since 80 the mean free path of the ions of the gas increases with a decrease in the gas pressure, it is found that the cathode fall of potential increases with a decrease in the gas pressure, providing however that the entire surface of the cathode is covered with the glow discharge. The cathode fall of potential, thus increased above the normal value above set forth, may be termed an abnormal cathode fall of potential.

In so far as I am aware, gaseous conduction lamps heretofore constructed and operated are characterized by the fact that in their operation the cathode fall of potential is maintained at a normal value. The operation of such prior gaseous conduction devices in this manner appears to have been devised for the purpose of maintaining at

a minimum value the heating of the cathode and thereby also to minimize the disintegration of the material of the cathode and to prevent the occlusion by the particles disintegrated from the cathode of the gases within the device.

As distinguished from such prior devices, it may be said to be one of the features of this invention to maintain the cathode drop 10 in potential at an abnormal value. Because of the phenomena that take place when the cathode drop in potential is maintained at an abnormal value, it has been found possible to give a gaseous conduction device an operating characteristic in which the cathode drop in potential is found to increase as the current intensity increases. This action, it is believed, will be clearly understood from the considerations herein- 20 before set forth. A gaseous conduction device or lamp having such a characteristic may, therefore, be connected directly into an electric circuit without necessitating the interposition of a protective resistance, since 25 a tendency to increase the current intensity passing through the device for any reason, such as, for example, an increase in the applied voltage, is met by a corresponding increase in the cathode fall of potential. The 30 cathode fall of potential may thus be considered as a counter electromotive force proportional directly to the current intensity and acts to protect or safeguard automatically the device against overloading. It will 35 thus be seen that the inclusion of a resistance in the circuit of the lamp may be entirely dispensed with and may be made only where it is desired to provide additional safeguarding of the device. Even where a resistance 40 may be inserted in the circuit of the lamp it will be seen that the value of the resistance may be made exceedingly small because of the inherent self-protecting qualities of the 45 gaseous conduction device itself and that hence only a minimum and substantially inconsequential dissipation of energy takes place in the resistance where it happens to be included in the circuit.

It will furthermore be seen that either by 50 dispensing entirely with a protective resistance in the circuit of the lamp or by reducing its effective value for the reasons hereinabove set forth a greater portion of the applied or circuit voltage becomes available 55 for utilization in the luminous column of the lamp, thus materially increasing the efficiency of the device or lamp. In order further to effectively utilize the increased energy consumed in that portion of the device where the cathode fall of potential is abnormal as hereinbefore set forth, provision is made in accordance with one of the features of this invention to make available 60 as an effective and efficient source of light 65 the glow covering the surface of the cathode,

which glow it will be noted substantially entirely covers the entire cathode surface, since the cathode drop of potential is maintained at an abnormal value.

In the drawing there is illustratively 70 shown in central vertical cross section an embodiment of my invention. There is shown at 1 a vessel adapted to contain a content of a gas or gases of the helium group, as hereinbefore set forth, or may also contain a gas such as nitrogen, for example. The vessel 1 has mounted in its upper end an electrode 3 which may take the form of a sheet of metal such as iron or nickel, for example. The electrode 3, which takes the 75 form of the anode in the operation of the device, may be mounted within the vessel 1 which may be made of a suitable material, such as glass for example, in any suitable manner and a conductor 3^a is adapted to 80 make electrical connection from the exterior 85 of the vessel 1 to the anode 3.

The vessel 1 at its lower end is preferably 90 of greater cross section to provide a cathode receiving chamber, indicated at 2, which, as will be seen from the drawing, forms an extension of the main portion of the vessel 1. The cathode or other electrode adapted to cooperate with the anode 3 to bring about a 95 luminous discharge within the gaseous content preferably takes the form of a substantially cylindrical sheet metal member 4 which may conveniently be mounted within the cathode receiving chamber 2 so as to be supported by the side walls of the latter, the 100 cathode 4 forming in effect a lining for the cylindrical walls of the cathode chamber 2. The cathode 4 may be made of a suitable metal such as a metal of the alkali group, or 105 may be made of an alloy including metals of the alkali group.

As will be more clearly hereinafter set forth, the glow discharge within the device when in operation covers substantially the entire surface of the cathode 4 and, as will 110 be seen from the drawing, the surface of the cathode 4 that will thus be covered by the glow will be the interior cylindrical surface of the cathode 4. In order to utilize effectively the glow covering the surface of the 115 cathode 4 there is mounted within the vessel 1 and preferably within the cathode chamber 2 a suitable reflector 5. The reflector 5 is conical in shape and may, for example, be made of glass or other suitable material 120 adapted to present on its exterior surface a surface well adapted for the reflection of light rays. The reflector 5 positioned substantially as illustratively set forth in the drawing will reflect the light rays indicated 125 by the arrows *a* coming from the luminous glow covering the surface of the cathode 4 outwardly as indicated by the arrows *b*, thus directing outwardly from the interior of the cathode chamber 2 the light rays 130

emanating from the glow which, as hereinbefore noted, covers substantially the entire interior surface of the cathode 4.

The area of the surface of the cathode 4 is, as will be noted, materially greater than the area of the surface of the anode 3. The pressure of the gaseous content within the device is made relatively small, thus to increase the mean free path of the ions passing to the cathode 4 so that the velocity of the ions, as well as the rate of diffusion thereof, is materially increased. With such an increase in the velocity and diffusion of the ions and with the large available cathode surface the lamp when in operation will be characterized by a glow which will substantially entirely cover the surface of the anode 4, under which conditions, as has been hereinbefore set forth at length, the cathode drop of potential will assume a value characterized hereinbefore as abnormal. The lamp is thus not only made self-protective electrically since an increase in the current density will cause a corresponding increase in the cathode fall of potential acting in the nature of a counter E. M. F., but also more efficient since the glow covering substantially entirely the entire surface of the cathode is made available as a source of light.

The reflector 5 may be secured in place within the vessel 1 or within the cathode chamber 2 by any suitable means, such as a suspension 5^a, suitable openings 6 being provided to permit the gaseous discharge to pass from one electrode to the other. A conductor, indicated diagrammatically at 4^a, serves to connect the cathode 4 with the exterior of the vessel 1. The lamp, as hereinbefore described may also be operated upon alternating current as well as direct and it will be seen that the luminous column or the luminous portions of the discharge which may extend upwardly through the vessel 1 to the anode 3 are supplemented as a source of light by the glow covering the cathode surface and resulting from the maintenance in the device of an abnormal cathode fall of potential.

It will thus be seen that there has been provided in this invention a gaseous conduction lamp in which the several objects hereinbefore set forth as well as others are attained and that many advantages are achieved. There has been provided a gaseous conduction lamp which functions not only as an efficient source of light, but also operates to substantially automatically protect itself against overloading electrically.

As many possible embodiments might be made of the above invention and as many changes might be made in the embodiment above set forth, it is to be understood that all matter hereinbefore set forth or shown in the accompanying drawing is to be in-

terpreted as illustrative and not in a limiting sense.

I claim as my invention:

1. A gaseous conduction lamp, comprising, in combination, a vessel having translucent walls and containing a gas of relatively high conductivity, an anode mounted within said vessel, and a cathode mounted within said vessel and adapted to cooperate with said anode to maintain therebetween a luminous discharge, said gas being at a pressure such that substantially the entire surface of said cathode is covered with the glow forming part of said discharge in said gas.

2. A gaseous conduction lamp, comprising, in combination, a vessel having translucent walls and having a gaseous content including a gas of the helium group, an anode mounted within said vessel, and a cathode also mounted within said vessel having its effective surface so arranged with respect to said anode and said gas being at such a pressure that an increase in current due to a rise in voltage applied to said electrodes causes an increase in the cathode fall of potential.

3. A gaseous conduction lamp, comprising, in combination, a vessel having translucent walls and containing a gas of high conductivity, an anode within said vessel, a cathode mounted within said vessel and having spaced oppositely disposed portions, the facing surfaces of which are adapted to cooperate with said anode to maintain therebetween a luminous discharge, said gas being at a pressure such that substantially the entire surface of said cathode is covered with the glow forming part of said discharge, and means within said vessel and associated with said cathode for reflecting outwardly the light rays emanating from the glow covering the facing surfaces of said cathode.

4. A gaseous conduction lamp, comprising, in combination, a vessel having translucent walls and containing a gas of relatively high conductivity, an anode mounted within said vessel, a cathode having the form of a hollow cylinder mounted within said vessel and adapted to cooperate with said anode to maintain therebetween a luminous discharge, said gas being at a pressure such that at least the entire interior surface of said cylindrical cathode is covered with the glow forming part of said discharge, and means mounted substantially within said cylindrical cathode for directing light rays emanating from said glow on said interior surface of said cathode in a direction substantially axial with respect to said cylindrical cathode.

5. The method of operating a gaseous conduction lamp having an anode and a cathode adapted to maintain a luminous discharge in a gaseous content including a gas of high

conductivity, which consists in increasing the intensity of the current passing from the anode to the cathode to a point where the cathode drop of potential becomes ab-
normal, whereby a further increase in the current intensity is met with a substantially corresponding increase in the cathode drop of potential.

6. The method of operating a gaseous con-
10 duction lamp having an anode and a cathode adapted to maintain a luminous discharge in a gaseous content including a gas of high conductivity, which consists in increasing

the intensity of the current passing from the anode to the cathode to a point where 15 substantially the entire surface of the cathode is covered with the glow forming part of the luminous discharge between said anode and said cathode and in utilizing said glow covering the surface of said cathode 20 to supplement as a source of light the luminous portions of said glow discharge.

In testimony whereof I affix my signature.

DR. FRITZ SCHRÖTER.
